PORTABLE EXERCISE TREADMILL

Joseph A. Hesen, 2415 N. Parish Place,
Burbank, Calif. 91504

Filed May 17, 1968, Ser. No. 11,982

Term of patent 14 years

Int. Cl. D21—03

U.S. Cl. D34—5

FIG. 1 is a perspective view of a portable exercise treadmill showing my new design;

FIG. 2 is a top plan view thereof;

FIG. 3 is a left elevational view thereof;

FIG. 4 is a rear view of the treadmill as seen from the right of FIG. 3;

FIG. 5 is a front elevational view of a portable exercise treadmill as seen from the left of FIG. 3;

FIG. 6 is a perspective view of the portable exercise treadmill showing a straight handle assembly mounted to the base frame rather than to the cabinet, as illustrated in FIG. 1; and

FIG. 7 is a perspective view of the treadmill illustrated in FIG. 1 with the handle removed and showing a pair of

substantially horizontal parallel bar handle assemblies, each mounted respectively to a side of the base frame.

I claim:

The ornamental design for a portable exercise treadmill, as shown.
